CLAIM

The ornamental design for a partition for a commercial aircraft passenger cabin, as shown and described.

DESCRIPTION

FIG. 1 is a front, right perspective view of a partition for a commercial aircraft passenger cabin according to my design;

FIG. 2 is a top plan view thereof;

FIG. 3 is a right side elevation view thereof;

FIG. 4 is a front elevation view thereof;

FIG. 5 is a left side elevation view thereof;

FIG. 6 is a front, right side perspective view of the partition of FIG. 1 shown with commercial aircraft passenger cabin seats, ottoman and additional partition;

FIG. 7 is top plan view of the partition of the partition of FIG. 1 shown with commercial aircraft passenger cabin seats, ottoman and additional partition;

FIG. 8 is a front, left perspective view of the partition of FIG. 1 shown in a commercial aircraft passenger cabin;

FIG. 9 is a top plan view of the partition and cabin shown in FIG. 8;

FIG. 10 is a top plan view of the partition of FIG. 1 shown as being a part of a larger partition;

FIG. 11 is a top plan view of the partition of FIG. 1 shown as being a part of the larger partition, with commercial aircraft passenger cabin seats, ottomans and additional partitions;

FIG. 12 is a top plan view of the partition of FIG. 1 shown as being a part of the larger partition, in a commercial aircraft passenger cabin; and,

FIG. 13 is front, left perspective view of the partition and cabin shown in FIG. 12.

No bottom plan and rear elevation views are included as no features of the claimed design are visible therein.

Throughout the Figures, the broken lines on the partition represent the unclaimed boundaries of the claimed design, with the shaded areas being part of the claimed design and the non-shaded areas forming no part of the claimed design. The broken lines showing environment are for illustrative purposes only and form no part of the claimed design.

A mirror image of the partition shown in the drawings is within the scope of the claimed design.
